(57) **CLAIM**

The ornamental design for a camera, as shown and described.

DESCRIPTION

FIG. 1 is a perspective view of a camera showing our new design with a lens assembly tilted at a first position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left side view of the camera showing the lens assembly tilted in a second position; and,

FIG. 9 is a left side view of the camera showing the lens assembly tilted in a third position.

The broken lines are for the purpose of illustrating portions of the camera and form no part of the claimed design.

1 Claim, 6 Drawing Sheets
